UNITED STATES PATENT OFFICE.

JOSEPH KLEIN, OF PORT HURON, MICHIGAN, ASSIGNOR OF ONE-HALF TO
EUGENE J. SCHOOLCRAFT, OF PORT HURON, MICHIGAN.

SOOT-CATCHER.

No. 796,434.

Specification of Letters Patent.

Patented Aug. 8, 1905.

Application filed November 14, 1904. Serial No. 232,752.

To all whom it may concern:

Be it known that I, JOSEPH KLEIN, a citizen of the United States, residing at Port Huron, in the county of St. Clair and State of Michigan, have invented new and useful Improvements in Soot-Catchers, of which the following is a specification.

My invention pertains to soot-catchers for use in connection with stoves, more particularly heating-stoves and other furnaces; and it has for its object to provide a device adapted to collect soot and prevent the same from gathering in a stovepipe or a chimney and through the medium of which the collected soot may be quickly and easily returned to the stove or furnace at intervals to be consumed.

With the foregoing in mind the invention will be fully understood from the following description and claim when taken in connection with the accompanying drawings, forming part of this specification, in which—

Figure 1 is a view, partly in vertical section and partly in elevation, of my novel device as applied. Fig. 2 is a detail vertical section of the device, taken in a plane at right angles to Fig. 1; and Fig. 3 is a side elevation of the device.

Similar letters designate corresponding parts in all of the views of the drawings, referring to which—

B is my novel device as a whole.

C is a pipe for connecting the device and the flange around the smoke-opening of a stove or furnace, and D is a pipe for connecting the device and a chimney or for conducting smoke and gases from the device to the open air. In connection with the said pipe D, I prefer to employ a pipe E, which terminates at its lower end in a hood F and is designed to conduct foul air and vapors to the pipe D, and thereby prevent the objectionable dissemination of such air and vapors throughout a house.

The device B constitutes the present and preferred embodiment of my invention and comprises a circular casing b, interposed between and communicating with the pipes C and D and having an aperture c in one of its side walls; a disk d, pivoted on said side wall of the casing, Fig. 3, and having an aperture e adapted to be registered with the aperture c; a bearing f, fixed on the inner side of one of the side walls of casing b; a shaft g, journaled in the other side wall of the casing and

terminating at its outer end in a crank h; a frame i, fixed on the inner end of the shaft g; a frame j, having a trunnion k journaled in the bearing f; a circular screen m, preferably of wire mesh, surrounding and fixed on the frames i and j; a brush n, preferably of wire, arranged to engage the perimeter of the screen m, Fig. 2, a bar p carrying the said brush and connected in a hinged manner to the inner side of the circular wall of the casing b, and a handle r, connected to the said bar and extending loosely through an aperture in said circular wall of the casing B.

In the practical use of my novel device it will be observed that by reason of the screen m forming the convex surface of a drum the smoke and other products of combustion from the stove or furnace will pass twice through the said screen m *en route* to the pipe D. From this it follows that the soot which is present in the smoke, especially when the fuel used is soft coal, will be caught on the screen m, and hence prevented from gathering in the pipe D and rendering frequent cleaning thereof necessary. When the portions of the screen m opposite the pipes C and D have been covered with soot, the drum formed by the said screen m, the frames i and j, and the crank-shaft g may be turned so as to dispose fresh portions of the screen in alinement with the pipes C and D. It will also be observed that when a considerable amount of soot is collected on the screen m of the rotary drum and the said drum is rotated through the medium of the crank-shaft the brush n, especially when said brush is pressed inwardly, will operate to remove the soot from the screen m, with the result that the soot will fall back into the stove or furnace and be consumed, and the screen m will be left clear for future use.

When fresh fuel is put into the stove, the disk d is positioned to close the opening c, and said opening c is kept closed until the fire is well under way. The aperture e in disk d is then registered with the opening c, so that dry air will be drawn from the room, and the smoke will be kept from condensing before it gets through the pipe.

It will be appreciated from the foregoing that my novel device when properly attended to will assure the smoke-conduit leading from a stove or other furnace being at all times clear, so as to afford a good draft, and will obviate the necessity of taking the said pipe

down for cleaning at frequent intervals. It will also be appreciated that the device is simple and compact in construction and is well adapted to withstand the usage to which soot-catchers are ordinarily subjected.

I have entered into a detailed description of the construction and relative arrangement of the parts embraced in the present and preferred embodiment of my invention in order to impart a full, clear, and exact understanding of the said embodiment. I desire it understood, however, that such changes or modifications may be made in practice as fairly fall within the scope of my invention as claimed.

Having described my invention, what I claim, and desire to secure by Letters Patent, is—

A soot-catcher for smoke-conduits, comprising a casing having an inlet in its lower portion and an outlet in its upper portion, where-

by it is adapted to form part of an uptake, a bearing fixed at the inner side of one of the upright walls of the casing, a shaft journaled in the other upright wall thereof and having a crank disposed outside of the casing, a frame having a trunnion journaled in the bearing, a frame fixed on the crank-shaft, a cylindrical screen surrounding and connected to the said frames and located between the inlet and the outlet of the casing, and a device arranged to engage the outer side of the said screen, whereby when the screen is rotated it will be cleared of collected soot.

In testimony whereof I have hereunto set my hand in presence of two subscribing witnesses.

JOSEPH KLEIN.
